TROUSER GUARD

Bernhard Hochberg, Brooklyn, N. Y.

Application August 14, 1936, Serial No. 95,948

1 Claim. (Cl. 2—231)

This invention relates to improvements in protectors for men's trousers and has for its principal object the provision of an improved liner structure which is attached to each side of the inside 5 crotch portion of the man's trousers for the prevention of soiling or discoloration, occasioned by involuntary urinal leakage of the wearer.

Protectors of this character are generally known in the art but they for the most part have 10 been constructed in such a manner as to be ill-fitting and uncomfortable to the wearer. Accordingly, it is one of the objects of the present invention to provide an improved protector constructed of two separate portions, one for attachment to each side of the crotch portion of the trousers, the individual portions being shaped in such a manner as to readily fit trousers of any size or character. The protector is adapted to be 15 stitched or otherwise secured to the trousers, and is designed to prevent discoloration and consequent weakening of the fabric.

In trousers and like garments, the leg portions thereof which are contiguous to the crotch, are subjected to a considerable amount of friction by 20 the rubbing together of the two surfaces of material as one walks. When wear begins to occur at this point, it extends rapidly, and it is a further object of the present invention to provide means for reinforcing this crotch portion in such 25 a manner as to greatly increase the effective life of the trousers.

A still further object of the invention is the provision of an improved trouser protector which may be secured to the inner portions of the crotch 30 of the trousers in such a manner as to be entirely unnoticeable when viewed externally.

In the drawing:

Fig. 1 is a front elevation of a man's trousers, the view showing in broken lines the position of 35 the trouser protector when stitched in place;

Fig. 2 is a plan view of the two portions of the blank which constitute the preferred embodiment of the invention; and

Fig. 3 is a rear perspective view of the protector. 40 It will be noted from an examination of Fig. 2 that the embodiment consists of two irregularly shaped portions or sections 10 and 11 which are stitched together along the seam line 12, which seam line when in place in the trousers occupies 45 a position adjacent to the transverse seam line on the crotch of the trousers. These two portions are preferably made from rubberized material having a fabric backing, the rubberized surface 50 facing the inner portion of the trousers. Each of the portions 10 and 11 are somewhat differently 55

shaped in order to more perfectly fit the adjacent portion of the trousers. The portion 10 is formed with a substantially straight edge 13 at the base, a curved side edge 14, and a curved inner edge 15 which is relatively closely adjacent to the median 5 line a—a. The two curved edges 14 and 15 terminate in a straight edge 16 which occupies a generally horizontal position when the tapered, narrow upper portion 17 is suitably stitched to the inner fly portion of the trousers.

The adjacent portion 11, which is positioned on the right hand side of the trousers, is formed with a base edge 19, a curved outer edge 20 and a curved inner edge 21, the edge 21 having a somewhat greater curve than the edge 15 and the inner portion thereof is substantially twice as far from the median line a—a as is the inner portion of the edge 15. Likewise, these curved edges 20 and 21 terminate in a short straight edge 22, thereby forming the narrowed portion 23. It will 20 be noted from an examination of Fig. 2 that the upper edge 16 which defines the terminal of the narrowed portion 17, extends further beyond the median line a—a than does the edge 22, all in order to cause the protector to fit the trousers in a 25 more satisfactory manner. The edges of the protector may be either reinforced with a tape 24 or, in the event that a less expensive construction is desired, the edges may be simply pinked.

Fig. 3 is a rear elevation showing the position 30 of the protector when the same is stitched to the garment. The lower ends of the portions 10 and 11 are adjacent to the seat portion of the trousers and accordingly occupy a generally horizontal position, whereas the narrowed portions 17 and 23 35 are substantially vertical and the opposed edges 15 and 21 become substantially parallel to each other. The portion 11 is, as aforesaid, secured to the right hand section 26 of the trousers. The inner edge 21 of this portion is stitched along a 40 line which corresponds generally with the marginal edge 27 of the inner fly portion when the trousers are closed. The inner edge 15 of the portion 10 is stitched to the left hand section 29 of the trousers along a line which corresponds with the marginal edge 28 of the right hand fly section. In other words, when the trousers are closed, the 45 protector covers the entire crotch portion thereof except the relatively narrow strip of the inner fly portion which serves as the base for the buttons.

The stitched edge 12 joining the two portions 10 and 11 may be suitably secured to the transverse seam in the crotch portion of the trousers. It is not necessary to secure the outer curved edges 14 and 20 to the trousers, although this 50 55

may be done if so desired. By forming the inner curved edges 15 and 21 in the manner shown, the protector, when stitched in place in the trousers, assumes a perfectly flat position and closely hugs 5 the garment. It is also yieldable to accommodate the various movements of the wearer and is generally inconspicuous in appearance.

It will be appreciated of course, that the two 10 sections of the blank constituting the present invention which is illustrated and described herein may be considerably modified both in shape and size without departing from the spirit of the invention. Also, the blank may be made from a wide variety of materials, preferably those of 15 a waterproof nature. Therefore, the invention is to be broadly construed and not to be limited except by the claim appended hereto.

What I claim is:

10 A trouser protector adapted to be secured to the 20 inner surface of the crotch portion and upper

front portion of a pair of trousers, said protector comprising a plurality of blanks of rubberized material stitched together along a substantially straight line of seam, each of said blanks having a base portion provided with curved upwardly 5 extending outer side edges and concavely curved upwardly extending inner side edges, the inner and outer curved edges of each blank converging together to form a progressively narrowed extension portion of the base portion, the upper terminals of the extension portions overlapping each other when the blank is lying flat, said protector being adapted to be secured adjacent to the crotch seam of the trousers along said line of seam joining the blanks, the base portion being adapted to 10 follow the curvature of the body and the upwardly extending portions being adapted to be secured to the upper front meeting portions of the trousers. 15

BERNHARD HOCHBERG. 20
